UNITED STATES PATENT OFFICE.

JOHN HOLLAND-LETZ AND WILLIAM HOLLAND-LETZ, OF CROWN POINT, INDIANA,
ASSIGNORS TO THE LETZ MANUFACTURING COMPANY, OF CROWN POINT, INDIANA,
A CORPORATION OF INDIANA.

GRINDING-MACHINE.

1,197,491.

Specification of Letters Patent.

Patented Sept. 5, 1916.

Application filed February 18, 1915. Serial No. 9,051.

To all whom it may concern:

Be it known that we, JOHN HOLLAND-LETZ and WILLIAM HOLLAND-LETZ, citizens of the United States, and residents of Crown

5 Point, in the county of Lake and State of Indiana, have invented certain new and useful Improvements in Grinding-Machines, of which the following is a full, clear, and exact specification.

10 Our invention is concerned with grinding machines of the general class shown in the patent to Holland-Letz, No. 1,077,714, dated November 4, 1913, and is designed to simplify and thereby improve the construction 15 and mounting of the stationary bur without interfering with its necessary freedom of movement during the grinding operation.

To illustrate our invention, we annex hereto a sheet of drawings, in which the 20 same reference characters are used to designate identical parts in all the figures, of which,—

Figure 1 is a central longitudinal vertical section through a portion of a grinding mill 25 containing our improvement; Fig. 2 is a horizontal cross section of the same; Fig. 3 is a view of the back of the casing, with the burs removed; Fig. 4 is a similar view, with the stationary bur in place; and Fig. 5 is 30 a rear elevation of the stationary bur.

In carrying out our invention, any desired form of a casing for the burs may be employed, but we preferably employ the two-part casing having the rear part 10 and 35 the front part 11, the front part being associated with the bearing 12 for the grinding shaft 13, which extends through the casing and is suitably journaled in the other end of the casing 14 which supports the hopper. 40 The rotating bur 15 may be of any desired construction, provided it is suitably designed to coöperate with the stationary bur.

The structure thus far described may be 45 of any suitable construction, and forms no part of our present invention.

The rear part 10 of the casing is of a generally cup-shaped form, and has lugs 16 and 50 17 at the sides thereof and coöoperating with similar lugs 18 and 19 formed on the front portion 11 of the casing, these lugs having apertures therein for the locking bolts 20, which serve to secure the two parts of the case together. The inner face of the rear portion 10 of the casing is provided with

two annular flanges 21 and 22, which co- 55 operate to form an annular channel, which is filled with some suitable packing 23. The stationary bur 24 has on its rear face an annular flange 25, which is of suitable size and shape to enter the channel and coöperate 60 with the packing 23 to prevent the escape of the material to be ground as it passes through the opening 26 to the grinding position between the two burs. The opposed faces of the two burs may have any desired 65 configuration, as indicated at 27.

The casing 10 has on its inner face three equi-distant lugs 28, each of which has an inclined face 29 adapted to coöperate with a similarly inclined face 30 on the rear of 70 the three similarly disposed lugs 31 projecting rearwardly from the periphery of the stationary bur 24. The bur 24 also has a pair of radially disposed lugs 32 and 33, which are adapted to coöperate with lugs 34, 75 35 and 36, respectively, projecting from the inner periphery of the rear portion 10 of the casing in the same vertical plane. The coöperating action of these lugs 32, 33, 34, 35 and 36 serves to prevent the possible rotation of the stationary bur 24 as a result of the movement of the rotating bur, while not interfering at all with the movements of the stationary bur to and from the rotating bur necessary to accommodate the materials 80 being ground as they pass between the burs. The coöperating action of the lugs 28 and 31 serves to center the stationary bur accurately, and we have found by actual practice that this simplified construction works just 85 as freely, and is much more durable and desirable than the more complicated construction shown in the aforesaid Patent No. 1,077,714, where two additional annuli were employed to secure the desired trammeling 90 movement of the stationary bur.

What we claim as new, and desire to secure by Letters Patent of the United States, is:

1. In a grinding machine, the combination with a grinding casing member having a centrally located feeding aperture therein, of a stationary bur member, consisting of an annular disk having a central feeding aperture registering with the grinding-casing- 100 member feeding-aperture, one of said members having a plurality of bearing surfaces projecting beyond its face near its periphery 105

on the side adjacent the other member, and said other member having a similar plurality of correspondingly inclined bearing surfaces engaging the coöperating surfaces, connections between the casing member and the bur member to prevent the rotation of the latter while not interfering with its movement to and from the casing, connections between the adjacent faces of the casing member and bur member adjacent the feeding apertures to prevent the material passing between said adjacent faces, a shaft extending into the casing member, and a second bur coöperating with the first-mentioned bur-member secured on said shaft to rotate therewith.

2. In a grinding machine, the combination with a grinding casing member having a centrally located feeding aperture therein closely surrounded by an annular channel, of a stationary bur member consisting of an annular disk having a central feeding aperture registering with the grinding-casing-member feeding-aperture and surrounded by an annular flange on its rear face projecting into the aforesaid annular channel, both of said members having a plurality of inclined bearing surfaces projecting beyond the adjacent faces near their peripheries and co-operating with the corresponding bearing surfaces on the other member, packing in the

annular channel adapted to be engaged by the annular flange, connections between the casing member and the bur member to prevent rotation of the latter while not interfering with its movement to and from the casing, a shaft extending into the casing member, and a second bur coöperating with the first secured on said shaft to rotate therewith. 35

3. In a grinding machine, the combination with a grinding casing member, of a stationary bur member, said members being provided with contacting surfaces to permit of the proper centering of the bur member, connections between the casing and the bur to prevent the rotation of the latter, a shaft 40 extending into the casing, a second bur coöperating with the first secured on said shaft to rotate therewith, and a casing cover member coöperating with the casing member and overhanging portions of the stationary 45 bur member to limit the movement of the same away from the casing member.

In witness whereof, we have hereunto set our hands and affixed our seals, this 6th day of February, A. D. 1915.
